UNITED STATES PATENT OFFICE

143,169

DESIGN FOR A DOLL OR SIMILAR ARTICLE

Richard C. Russell and Jefferine D. Russell,
Monterey Park, Calif.

Application January 25, 1945, Serial No. 117,602

Term of patent 7 years

(Cl. D34—4)

To all whom it may concern:

Be it known that we, Richard C. Russell and Jefferine D. Russell, citizens of the United States, residents of Monterey Park, in the county of Los Angeles, State of California, have invented a new, original, and ornamental Design for a Doll or Similar Article, of which the following is a specification, reference being had to the accompanying drawing, forming part thereof.

We claim:

The ornamental design for a doll or similar article, as shown.

RICHARD C. RUSSELL.
JEFFERINE D. RUSSELL.
